JAN 30, 1883

UNITED STATES PATENT OFFICE.

JOHN L. POPE, OF CLEVELAND, OHIO.

DESIGN FOR A HARNESS-BIT.

SPECIFICATION forming part of Design No. 13,552, dated January 30, 1883.

Application filed November 11, 1882. Term of patent 14 years.

To all whom it may concern:

Be it known that I, JOHN L. POPE, of Cleveland, in the county of Cuyahoga and State of Ohio, have invented and produced a new and original Design for Harness-Bits, of which the following is a specification, reference being had to the accompanying photographs, making a part thereof.

My invention relates to a novel design for the cheek-pieces and rings of harness-bits; and it consists in certain features of contour which will be hereinafter more particularly described and claimed.

Two photographs are presented with this specification. That marked Figure 1 illustrates what is known as a "half-cheek" snaffle-bit, and that marked Fig. 2 illustrates what is known as a "full-cheek" snaffle-bit.

My invention rests principally in the design of the cheek-piece, and it of course may be used in either a half-cheek or a full-cheek bit.

In both views similar parts have like letters of reference.

A is the bit proper. B B are two rings, to which are attached the reins, &c.; and C C are the "cheek-pieces," so called. The rings and cheek-pieces are cast entire in one piece of metal. The general contour of the cheek is that of a tapering frame, the smallest portion

of which adjoins the ring and lies nearest the bit. The sides of this open frame C diverge as they leave the ring until the points c are reached, where the outer edges are rounded. Then the outer edges of the frame continue to spread in straight lines down until the end bar 35 of the frame is met. From the points c the inner edges of the frame curve inwardly down to the end bar, e, which latter is made slightly curved, and with a little projection about midway of its length. 40

It will be understood that my novel design of cheek-piece may be used with a half-cheek or a full-cheek bit, and with a snaffle or other kind of bit.

What I claim as my invention, and desire to secure by Design Letters Patent, is—

1. A harness-bit the cheek-pieces of which form in general outline a tapering frame, substantially as shown and described.

2. A harness-bit the rings and cheek-pieces 50 of which have substantially the form shown and described.

In testimony whereof I have hereunto set my hand this 3d day of November, 1882.

JOHN L. POPE.

In presence of—

WALTER A. BIDDLE,
GEORGE F. EBERHARD.
